CANNED LIQUID DISPENSER

Filed April 23, 1947

UNITED STATES PATENT OFFICE

2,537,899

CANNED LIQUID DISPENSER

Everett A. La Dow, Detroit, Mich.

Application April 23, 1947, Serial No. 743,232

6 Claims. (Cl. 222—83.5)

This invention relates to dispensing devices and in particular to canned liquid dispensers.

One object of this invention is to provide a canned liquid dispenser which will receive, hold and conceal a can of liquid and which has self-contained mechanism therein for piercing the can and releasing its contents.

Another object is to provide a canned liquid dispenser having a tubular body for receiving the can and a top unit on the body containing one piercing device for admitting air to the can and another piercing device for providing a conduit which communicates with a spout for pouring out the contents of the can.

Another object is to provide a canned liquid dispenser having a tubular body for receiving the can and a top unit with a piercing mechanism which seals itself tightly with the edges of the opening which it creates, thereby preventing leakage of the liquid around the opening and accordingly providing a more sanitary dispenser than hitherto.

Another object is to provide a canned liquid dispenser, as set forth in the preceding objects, wherein the top unit is removable from the tubular body by a quickly detachable connection so that the dispenser is quickly and easily cleaned.

Another object is to provide a canned liquid dispenser, as set forth in the preceding objects, wherein the piercing devices are operated by mechanism connected to the handle by which the dispenser is subsequently held for pouring out the contents of the can, the closing motion of the handle operating the two piercing devices.

Another object is to provide a canned liquid dispenser, as set forth in the preceding objects, wherein the tubular piercing device for entering the can and pouring out the liquid is a pointed member with an angled cutting edge which reaches its maximum diameter at its point of final entry into the can cover, thereby providing a hinge connection for the flap detached from the can cover to fold downward upon without causing tearing of the can cover material and hence providing a tight seal around the piercing device.

In the drawing,

Figure 1 is a central vertical section through a canned liquid dispensing device, according to a preferred form of the invention, with the piercing mechanism about to be operated to enter the can cover;

Figure 2 is a horizontal section through the top of the dispensing device of Figure 1, with the top wall removed;

2

Figure 3 is a fragmentary central vertical section similar to Figure 1, but showing the position of the piercing devices after they have entered the can cover and the liquid is ready to be poured out of the can;

Figure 4 is an enlarged central vertical section through the lower wall and one of the detent devices for holding the can in the dispenser;

Figure 5 is a vertical section along the line 10 5—5 in Figure 2, showing the quickly detachable pin and slot connection between the top unit and the tubular body of the dispenser;

Figure 6 is a vertical section along the line 15 6—6 in Figure 1, showing the hollow piercing device for pouring out the liquid;

Figure 7 is a fragmentary top plan view of a portion of the can showing the aperture and folded flap made by the hollow piercing device in the can cover; and

Figure 8 is a cross-section through a modified can-piercing plunger of approximately semi-circular or semi-elliptical cross-section.

Referring to the drawings in detail, Figures 1 and 2 show a canned liquid dispenser, generally designated 10, according to a preferred form of the invention, with a can 11 containing the liquid to be dispensed in position prior to its being pierced. The dispenser 10 includes a tubular body unit 12 and a top unit generally designated 13 and 14 respectively, detachably secured thereto and containing the piercing mechanism and pouring spout.

The body unit 12 is tubular to conform to the shape of the can 11, and contains a bore 14 for receiving the can 11. The bore 14 is cylindrical in shape to receive a cylindrical can 11, but may also be of rectangular cross-section to receive a can of like shape. In order to retain the can within the bore 14, the lower rim 15 of the body unit 12 is provided with a plurality of transverse substantially radial bores 16 (Figures 1 and 4) containing detents generally designated 17. Each detent 17 consists of a tubular casing 18 containing a reciprocable rod 19 having a head 20 on the inner end and a handle 21 secured as at 22 to the rod 19. A coil spring 23 mounted within the casing 18 between the outer end wall 24 thereof and the head 20 urges the latter into a position projecting into the bore 14. The head 20 is provided with an angled end 25 to cause the head 20 to yield automatically when the can 11 is inserted, yet to spring back into position with its upper surface 26 beneath the bottom 27 of the can 11 after the latter has passed. The head 20 is grooved as at 28 to re-

ceive a lip or projection 29 from the casing 18, this serving as a key for preventing rotation of the head 29 in the reduced diameter counterbore 30 forming a continuation of the bore 16.

Adjacent the rim 15 near the lower edge of the body unit 12 a spring clamp 31 (Figure 1) is mounted and secured thereto by the screw 32 in the threaded hole 33. The spring clamp 31 is provided with a U-shaped bent portion 34 forming a recess shaped to receive the lower end 35 of a swinging handle 36. The upper portion of the handle 36 is provided with spaced parallel arms 37 (Figure 2) which pass on opposite sides of a lug 38 and are pivoted thereto by a pivot pin 39 passing through both arms 37 and the lug 38. The lug 38 projects upward from a disc-like plate 40, the edge portions 41 of which engage a flange 42 on the upper end of the body unit 12. The upper side of the edge portion 41 is in turn engaged by the flange portion 43 of a cup-like cover 44 having a hole 45 in the side wall thereof for the passage of the handle 36. Headed pins 46 (Figure 5) seated in sockets 47 in the rim portion 42 pass through keyhole slots 48, thereby forming a quickly detachable connection between the top unit 13 and body unit 12 (Figures 2 and 5). The cover 44 is secured to the plate 40 by means of screws 49 passing through the rim portion 43 of the cap 44 into the edge portion 41 of the plate 40 (Figure 2).

The ends of the arms 37 are bent toward one another (Figure 2) and are joined by a pivot pin 39 which passes through elongated slots 51 and 52 in the adjacent ends of rocking levers 53 and 54 respectively. The levers 53 and 54 are mounted upon lugs 55 and 56 by means of pivot pins 57 and 58 respectively passing therethrough.

The opposite end of the rocking lever 53 is provided with an elongated slot 59 engaging a pin 60 mounted in the bifurcated upper end 61 of a solid piercing plunger 62. The latter reciprocates vertically through a bore 63 in a lug 64 projecting upward from plate 40 (Figures 1 and 3). The lower end of the piercing plunger 62 is provided with a conical point 65 above which is a reduced diameter neck portion 66.

The outer end of the rocking lever 54 is slotted as at 67 to receive a pin 68 passing through the bifurcated upper end 69 (Figure 6) of a hollow piercing plunger 70. The latter is preferably of triangular cross section (Figure 2) and reciprocates vertically in a triangular bore 71 formed in a lug 72 projecting upward from the plate 40. The hollow piercing plunger 70 is provided with an L-shaped passageway 73 which extends from the inclined or oblique lower end 74 thereof upward and outward through the side wall of the plunger 70. It will be observed that the point 75 of the plunger 70 which first enters the can 11 is opposite the side 76 of the maximum width of the plunger 70. The side 76 enters the cover 77 of the can 11 at the very end of the piercing operation, preventing tearing in the manner explained in connection with the operation. The side wall of the lug 72 is provided with a bore 78 which receives the inner end of an upwardly bent pouring spout 79 which passes outward through a bore 80 in the cover 44. The spout 79 contains a passageway 81 for the passage of the liquid to be poured.

It will be observed from Figure 6 that the intermediate portion of the hollow piercing plunger 70 is slightly tapered as at 82 as it approaches the oblique lower end 74, thereby enhancing the seal

between it and the can cover which it pierces. The latter is also provided with inclined cutting edges 83 converging toward a junction with the vertical edge 85 at the point 75. While a triangular cross-section is preferred for the piercing plunger 70, a semi-circular cross-section may optionally be used, if desired.

Operation

In the operation of the dispenser 10, the handle 36 is pulled outward and upward into its solid line position (Figure 1) with its lower end 35 detached from the recess 34 in the spring clamp 31. This action raises the piercing plungers 62 and 70 to the tops of their strokes. The can 11 is then inserted through the mouth 86 of the bore 14 and pushed upward, the cover thereof engaging the inclined ends 25 of the detents 17 and pushing them aside. The detents 17 snap back beneath the bottom 27 of the can when the latter is in position (Figure 1). Since the dispenser 10 is preferably designed to receive a standard size of can, such as a condensed milk can, the bore 14 from the lower surface 87 of the plate 40 to the top edge 26 of the detent head 28 will have a length substantially equal to the height of such a can.

With the can 11 in position within the bore 14 and held by the detents 17, the handle 36 is pushed sharply downward and inward with one hand while the body unit 12 is held by the other hand. As the handle 36 moves into the dotted line position shown in Figure 1 and its lower end 35 snaps into the recess 34 of the spring clamp 31, the inner ends of the rocking levers 53 and 54 are swung upward into their dotted line positions (Figure 1) forcing the piercing plungers 62 and 70 downward in their bores 63 and 71, piercing the cover 77 of the can 11. The piercing plunger 62 forms a hole 88 of substantially the same diameter as the conical point 65 of the plunger, and the latter comes to rest in the position shown in Figure 3 with the neck portion 66 within the hole 88. This forms an annular air space between the neck 66 and hole 88 for the air to enter as the liquid is withdrawn.

Simultaneously with the downward motion of the solid piercing plunger 62, the hollow piercing plunger 70 also moves downward and pierces the cover 77 of the can 11. As the plunger 70 moves downward from the position shown in Figure 1 to that of Figure 3, the point 75 and inclined cutting edges 83 of the lower end 74 cut out a triangular hole 89 in the can cover 77 (Figure 7) bending downward the triangular flap 90 thereby produced (Figure 3). When the piercing plunger 70 has fully entered the can 11 (Figure 3), the side 76 of maximum width has entered the can cover 77 and the tapered intermediate portion has gradually enlarged the hole just before coming to a halt, enhancing the seal around it. As a consequence, the triangular flap 90 hinges at its upper edge 91 of maximum width (Figure 7).

This construction prevents tearing of the flap 90 or can cover 77 and insures a snug fit between the aperture 89 and the hollow piercing plunger 70. This in turn prevents leakage of the contents of the can 11 and hence provides a sanitary construction. In prior constructions, where a piercing plunger of circular cross-section has been employed, or where a plunger of greater than semi-circular cross-section has been employed, a tearing of the cover 77 of the can 11 has occurred by reason of the fact that the flap thereby detached does not hinge at its point of maximum width. In such prior constructions,

therefore, leakage occurred in the gap formed by the tear, thereby causing the liquid to soil the interior of the dispenser 10, with unsanitary results.

With the parts moved into their positions shown in Figure 3, the L-shaped passageway 73 in the piercing plunger 70 lines up with the bore 81 in the pouring spout 79 and the lower end 35 of the handle 36 snaps into the recess 34 in the spring clamp 31, holding the handle 36 securely in its dotted line position (Figure 1). The user now lifts the dispenser 10 by means of the handle 36, tilting it forward and downward to pour out the liquid from the can 11 through the passageway 73 and bore 81 in the piercing plunger 70 and spout 79 respectively. At the same time, air rushes in through the annular space around the neck 66 (Figure 3) replacing the liquid poured out.

When the can 11 is empty, the operator pulls the handle 36 upward to its solid-line position of Figure 1, retracting the plungers 62 and 79. He then grasps the heads 21 of the detents 17 in the fingers of his two hands and pulls them outward in opposite directions, whereupon the can 11 falls out of the bore 14 through the mouth 86 thereof. The device is then ready for the insertion of another can. To clean the top unit 13, the operator grasps the cover 44 and rotates it in a counterclockwise direction (Figure 2) until the heads of the pins 46 move into alignment with the enlargement of the keyhole slots 48. The top unit 13 may then be lifted off the body unit 12 and cleaned by passing a cloth over the surface 87 and by running a liquid through the passageway 73 and bore 81 with the two moved into alignment (Figure 3) by pressing the handle 36 downward.

The modified hollow piercing-plunger 91 shown in Figure 8 is similar in purpose to the plunger 70 shown in Figure 1 and likewise resembles the latter in longitudinal section as in Figure 1. The plunger 91 is, however, of approximately semi-circular or semi-elliptical cross-section, having an arcuate side wall 92 and a flat side wall 93 at the maximum width of the plunger. The side 93 thus forms a diameter of the cross-section—either the diameter of a semi-circle or the minor diameter of an ellipse. The plunger 91 is provided with a passageway 94 similar to the passageway 73, and likewise with an inclined or oblique lower end. The operation of the modification shown in Figure 8 is similar to that of the principal form of the invention, and similarly accomplishes the cutting out of a flap from the top of the can, bending it downward without tearing it since the rear wall 93 of the plunger is its maximum width in cross-section.

What I claim is:

1. A canned liquid dispenser, comprising a casing having a can-receiving recess therein and a top member closing the upper end of said recess, said top member having a pair of spaced longitudinally-directed bores positioned at opposite sides of said recess, a can-cover-piercing plunger reciprocably mounted in each of said bores, one of said plungers being hollow and having a liquid passageway therethrough, a movable plunger-operating element mounted on said top member, and mechanism on said top member operatively interconnecting said element and said plungers and responsive to the motion of said element for simultaneously urging said plungers downward relatively to said top member into piercing engagement with the cover of said can.

2. A canned liquid dispenser, comprising a casing having a can-receiving recess therein and a top member closing the upper end of said recess, said top member having a pair of spaced longitudinally-directed bores positioned at opposite sides of said recess, a can-cover-piercing plunger reciprocably mounted in each of said bores, one of said plungers being hollow and having a liquid passageway therethrough, a movable plunger-operating element comprising a handle pivotally mounted on said top member, and mechanism on said top member operatively interconnecting said element and said plungers and responsive to the motion of said element for simultaneously urging said plungers downward relatively to said top member into piercing engagement with the cover of said can.

3. A canned liquid dispenser, comprising a casing having a can-receiving recess therein and a top member closing the upper end of said recess, said top member having a pair of spaced longitudinally-directed bores positioned at opposite sides of said recess, a can-cover-piercing plunger reciprocably mounted in each of said bores, one of said plungers being hollow and having a liquid passageway therethrough, a movable plunger-operating element comprising a handle extending downward along said casing and having its upper portion pivotally mounted on said top member, and mechanism on said top member operatively interconnecting said element and said plungers and responsive to the motion of said element for simultaneously urging said plungers downward relatively to said top member into piercing engagement with the cover of said can.

4. A canned liquid dispenser, comprising a casing having a can-receiving recess therein and a top member closing the upper end of said recess, said top member having a pair of spaced longitudinally-directed bores positioned at opposite sides of said recess, a can-cover-piercing plunger reciprocably mounted in each of said bores, one of said plungers being hollow and having a liquid passageway therethrough, a movable plunger-operating element comprising a handle pivotally mounted on said top member, and mechanism on said top member operatively interconnecting said element and said plungers and responsive to the motion of said element for simultaneously urging said plungers downward relatively to said top member into piercing engagement with the cover of said can.

5. A canned liquid dispenser, comprising a casing having a can-receiving recess therein and a top member closing the upper end of said recess, said top member having a pair of spaced longitudinally-directed bores positioned at opposite sides of said recess, a can-cover-piercing plunger reciprocably mounted in each of said bores, one of said plungers being hollow and having a liquid passageway therethrough, a movable plunger-operating element comprising a handle extending downward along said casing and having its upper portion pivotally mounted on said top member, and mechanism on said top member operatively interconnecting said element and said plungers and responsive to the motion of said element for simultaneously urging said plungers downward relatively to said top member into piercing engagement with the cover of said can.

6. A canned liquid dispenser, comprising a casing having a can-receiving recess therein and a top member closing the upper end of said recess, said top member having a pair of spaced longitudinally-directed bores positioned at opposite

sides of said recess, a can-cover-piercing plunger reciprocably mounted in each of said bores, one of said plungers being hollow and having a liquid passageway therethrough, a tubular spout mounted on said top member and communicating with said hollow plunger passageway in the can-piercing position of said hollow plunger, a movable plunger-operating element mounted on said top member, and mechanism on said top member operatively interconnecting said element and said plungers and responsive to the motion of said element for simultaneously urging said plungers downward relatively to said top member into piercing engagement with the cover of said can.
